ILLUMINABLE MAILBOX

Harold Hirschfeld, 1281 101st St., Miami Beach, Fla.

Filed Mar. 31, 1960, Ser. No. 59,975

Term of patent 14 years

(Cl. D74—9)

I claim:

The ornamental design for an illuminable mailbox, substantially as shown and described.
